TOILET ARTICLE

Application filed May 14, 1928. Serial No. 277,581.

This invention relates to toilet articles, and is concerned particularly with compact and portable toilet articles to be carried on or about the person, such as vanity cases and 5 the like.

In order to be able to use a vanity case to best advantage, proper illumination of the features of the user is necessary, but frequently this is not possible, due to poor light 10 or darkness, so that proper illumination must be sought or the use of the vanity case abandoned.

It is the principal object of this invention to provide a vanity case which includes illuminating means to be used at will whenever 15 necessary to illuminate the face of the user, so that the features may be clearly visible in the mirror forming part of the vanity case. In accordance with this object, we have de- 20 vised a vanity case including the usual cosmetics and the small mirror preferably mounted in the lid of the case. As a means for providing artificial light at will whereby the use of the vanity case in dim light or 25 darkness is made possible, we provide in the case a small incandescent light which may be energized at will by a switch-controlled dry cell battery. The incandescent light is mounted in a reflector which is so arranged 30 that it will reflect light upon the face of the user whereby the features are clearly visible in the mirror mounted within the lid of the vanity case. The illuminating means is en- 35 ergized at will by manipulating a suitable contact device, and the electrical connections of the illuminating means are automatically broken when the vanity case is closed, this contact breaking arrangement including a push-rod connected to one of the contacts of 40 the incandescent light and being actuated to disconnect that contact when the lid of the case is closed down upon the cosmetic receptacle. This push-rod also acts to close a contact whenever the lid of the case is raised for 45 use, but the electrical circuit including this contact must be subsequently closed by manipulating the aforesaid contact device in order to complete the circuit through the incandescent light. In this way, the incan- 50 descent light may be energized at will, but

is automatically de-energized when the vanity case is closed.

For a better understanding of the invention, reference is made to the accompanying drawings, in which

Figures 1, 2, 3, and 4 show exterior views of our new vanity case;

Fig. 5 is a longitudinal cross-section taken along the line A—A of Fig. 2;

Fig. 6 illustrates the preferred arrangement of the visible contents of the vanity case when it is in open position;

Fig. 7 is a transverse cross-section taken along the line B—B of Fig. 4; and

Fig. 8 is a longitudinal cross-section taken along the line C—C of Fig. 4.

In these drawings, numeral 1 designates the case or cosmetic receptacle having a butt hinge 2 at one edge, which connects the lid 3 thereto. At one side of the case 1 is a 70 sliding switch or contact button 4 which may be actuated by the finger or thumb of the user. The usual swivel 5 for attaching a carrying chain or the like is provided at one end of the case 1, while a latch 6, releasable by button 7, normally holds the lid 3 in position on the case 1. A mat 9 secures a glass or polished metal mirror 10 within the lid 3. In a similar way, the powder, rouge and lip paste mat 17 fits within alignment ring 80 8, this mat having openings through which access may be had to powder 12, rouge 15, and lip paste 33. The powder 12 is in the form of a cake or sifter mounted in tray 13, the rouge cake or sifter 15 is similarly mounted in tray 16, and lip paste 33 is also similarly mounted in tray 34, these trays all being placed upon a removable partition 31, resting upon partition support 32, secured to the inside surface of case 1. In the openings 85 of mat 17 for access to powder cake 12 and rouge cake 15 are laid powder puff 11 and rouge puff 14, respectively.

In one corner of the case, preferably remote from the hinged mirror, is a receptacle 95 containing hemispherical reflector 19 of conducting material, having an attached screw threaded socket 26, in which incandescent light bulb 18 is screwed, this light bulb including the usual screw-base 25, which makes 100

one contact for the filament, and center contact 24, constituting the other contact for the filament. Adjacent one side of the reflector 19 and projecting through the mounting therefor is a push-rod 20 which is secured to a strip of insulation 21, in turn fastened to electrical contact spring 23 by rivets 22. This contact spring is secured to the inside wall of the light receptacle by means 10 of circuit making rivets 27, which are secured at their opposite ends in a contact plate 40. In order to insulate these contact pieces 23 and 40 from the inside wall of the case, strips of insulation 28 are interposed 15 between contact spring 23 and contact plate 40 and this side wall. Contact spring 23 is placed so that it lies directly beneath the center contact 24 of incandescent light bulb 18, so that when spring contact 23 is released 20 by disengagement of push-rod 20, this spring may make contact with center contact 24 of incandescent bulb 18.

Within the receptacle formed by the walls of the casing and partition 31 is placed a 25 three-cell dry battery 30, which is preferably of standard design and includes the electrolytic mixture 42 containing carbons 41, two of which are connected by jumper bars 39 to the metallic walls 43 of the adjacent cell, 30 these cells being insulated from each other and from the case 1 by strips of insulation 44. The terminal contact 38 of the third cell is adapted to make electrical connection with sliding contact 35, which is mounted upon 35 rivet 36, secured in the side of case 1. This sliding contact 35 is secured to push-button 4 by means of rivet 37, so that when push-button 4 is actuated, electrical connection is made between terminal contact 38 and sliding contact 35. Inasmuch as sliding contact 35 makes electrical contact with casing 1 and as reflector 19 and socket 26 are electrically connected to the case 1, the circuit is made from battery through contacts 38 40 and 35, case 1, reflector 19 and socket 26 to light bulb 18, and if the vanity case is open contact spring 23 is in connection with central contact 24 of light bulb 18, the electrical circuit through the bulb 18 is complete and 45 it will be illuminated. The other terminal of the battery 30 consists of a contact spring 29, which bears continuously against contact plate 40.

When using the vanity case, the user 50 presses button 7 in the usual way, thereby releasing lid 3 from catch 6, and inasmuch as push-rod 20 bears against mat 9 of lid 3, the contact spring 23, being released, pushes lid 3 upwardly a fraction of an inch so that 55 the user may grasp the lid and open it the remainder of the way. When contact spring 23 is released in the manner described, it engages central contact 24 of incandescent light bulb 18, thus placing the light in readiness for use, although the circuit is not com-

pleted until button 4 is pushed in the manner described. In the event that the light is poor and it is necessary to have additional illumination in order to properly use the vanity case, the user pushes button 4 to complete the electrical circuit from battery 30 through contacts 38 and 35, case 1, reflector 19, light socket 26, the filament of the light 18, central contact 24, contact spring 23, rivets 27, contact plate 40, and contact spring 29, back to battery 30. When the light bulb 18 is thus illuminated, the light therefrom is reflected upon the face of the user of the vanity case when the case is held in the usual way, so that the features are visible in the mirror 10 of the open lid 3. The reflector 19 is so shaped that the rays of light from the reflector 19 do not fall upon the mirror 10, so that the user is not blinded by reflected light. After the vanity case has been used and when the lid 3 is closed down upon the case 1 to be locked by latch 6, the mat 9 of the lid again engages push-rod 20, forcing it downwardly so that electrical connection between central contact 24 and contact spring 23 is broken, thus disconnecting the light bulb 18. The electrical circuit is broken in this way, even though the user fails to release push-button 4, but this push-button is so arranged that it must be held in closed position in order to keep contacts 38 and 35 in engagement. In this way the automatic circuit breaking arrangement is independent of the manual circuit-closing arrangement and it is immaterial to the 90 operation of the automatic circuit breaker whether the manually-operated contact-button 4 is in circuit closing position or not. In other words, the electric light bulb is always extinguished when lid 3 is closed down upon case 1. This conserves the energy of the battery and extends its life considerably, because it is only used when artificial illumination is required.

As the partition 31 is removable, the battery may be readily removed and replaced whenever desirable, and when this is done the battery is placed in operative position immediately because its spring contact 29 makes electrical connection with contact plate 110 40 while terminal contact 38 is placed in position for connection with sliding contact 36, whenever push-button 4 is manually actuated.

While the new toilet article has been illustrated and described as a preferred embodiment, it is to be understood that many changes may be made in form and detail within the scope of the invention, and further, although the device has been described as being used primarily for the application of cosmetics, the illuminating means may be used separately as a pocket flash-light whenever necessary, so that the new device is 120 125 130

both a pocket flash-light and a vanity case.

We claim:

1. In a vanity case, the combination of a receptacle for toilet articles, a lid for the receptacle permitting access to the interior thereof, a source of electrical energy in the receptacle, an incandescent bulb, a contact normally engaging the base of the bulb when the case is open, a push-rod secured to the contact, 5 said push-rod being engaged by the lid when closed to disconnect the contact, and a manual switch for connecting the bulb and the contact in the electrical circuit with said source.
- 15 2. In a vanity case, the combination of a receptacle for toilet articles, a lid for the receptacle permitting access to the interior thereof, a source of electrical energy in the receptacle, an incandescent bulb, a spring 20 contact normally engaging the base of the bulb and connecting the bulb to one terminal of said source when the case is open but disconnected therefrom when the case is closed, a push-rod on said contact arranged to be 25 actuated by closure of the lid to break said connection, and a sliding contact manually operated to connect the other terminal of said source in the light circuit.
3. In a vanity case, the combination of a 30 cosmetic receptacle, a lid therefor, a dry cell in the receptacle permitting access to the interior thereof, an incandescent bulb in the receptacle, a spring contact normally engaging the base of the bulb and connecting the 35 bulb to one terminal of the cell when the case is open but disconnected therefrom when the case is closed, a manually operated contact for connecting the bulb to the other terminal of the cell, and a push-rod mounted 40 on the spring contact for engagement with the lid of the case to disconnect said contact from the bulb when the case is closed.
4. In a vanity case, the combination of a 45 receptacle permitting access to the interior thereof, a lid therefor, a removable tray therein for containing cosmetics, a dry cell beneath the tray, an incandescent bulb in the receptacle, a spring contact normally engaging the bulb when the box is open but disconnected 50 therefrom when the case is closed, electrical connections between the contact and one terminal of the cell, a manually operated contact movably mounted on the receptacle for engagement with the other terminal of the cell, electrical connections between 55 said movable contact and the bulb, and a push-rod mounted on the spring contact to disconnect the same from the bulb, said push-rod being arranged to be actuated 60 by the lid when the case is closed.
5. In a vanity case, the combination of a 65 receptacle, a lid therefor, a removable tray therein for containing cosmetics, a dry cell beneath the tray, an incandescent light in the receptacle, a partition in the receptacle

between the cell and the light, a contact plate on the partition mounted for engagement by one terminal of the cell, a spring contact mounted on the partition for normal engagement with the central contact of the 70 light, electrical connections between the spring contact and said contact plate, a push-rod mounted on said spring contact and having a projection for engagement by the lid of the case when closed for disconnecting the 75 spring contact from the light, a movable contact arranged for engagement with the other terminal of the cell, and electrical connections between the movable contact and the light.

In testimony whereof we affix our signatures.
